UNITED STATES PATENT OFFICE.

CHARLES WILLSIE, OF WELLINGTON, KANSAS.

WIRE SUPPORT AND HOLDER.

SPECIFICATION forming part of Letters Patent No. 329,869, dated November 3, 1885.

Application filed August 17, 1885. Serial No. 174,642. (No model.)

To all whom it may concern:

Be it known that I, CHARLES WILLSIE, a citizen of the United States, residing at Wellington, in the county of Sumner and State of 5 Kansas, have invented certain new and useful Improvements in Wire Supports and Holders, of which the following is a specification, reference being had therein to the accompanying drawings.

10 My invention relates to a device for supporting and holding in place stretched wire; and it consists in the construction and arrangement of the parts, which will be more fully herein-after described, and pointed out in the claims.

15 The object of my invention is to provide a support and holder for stretched wires whenever used, which shall be simple in construction, easily and readily attached to any style of post or place of securing, and durable and effective in its use. I attain these objects by

20 the device illustrated in the accompanying drawings, wherein like letters of reference indicate similar parts in the several views, and in which—

25 Figure 1 is a perspective view of my improved wire support and holder, illustrated as attached to a post. Fig. 2 is a front elevation of the same. Fig. 3 is a side elevation of the same. Fig. 4 is a detail view in elevation of 30 my improved support and holder, shown as attached to a telephone or telegraph pole and supporting the wires thereof.

A indicates a pulley-wheel, constructed of any suitable material. B is a wheel of smaller 35 diameter than A, and so constructed as to fit into the groove *a* of A, the two wheels A and B being supported by a staple, C, one prong, *c*, of which passes through the center of wheel A, and the other prong, *c'*, passes through the 40 wheel B at one side of its center, as at *c'*. The wheel B is constructed of considerable thickness at its central portion, and gradually tapers off to a somewhat narrow periphery, so as to snugly fit into the groove *a* of the wheel 45 A. The periphery of the wheel B may be provided with notches or serrations *b*, extending partially around the same, so that the wire or rope passing between the two wheels A and B will be more firmly clinched by the notches 50 or serrations biting the said wire or rope. By

the arrangement of the wheel B as an eccentric a greater resistance is obtained against the strain that is brought to bear upon said wheel, and also by having the axis situated to one side of its center the wheel will allow the 55 wire or rope to be readily drawn through between the two wheels in one direction, and bite against said wire or rope when it is drawn in the reverse direction or against the eccentric wheel, and firmly secure it. The two prongs *c* 60 and *c'* of the staple C are headed over after being securely driven into the post or place of securing, while the perpendicular bar *c'* of the staple extends over the faces of the two wheels A and B, and acts as a sheave or casing 65 for the same, leaving just enough space between the wheels and the staple as to allow of a free movement of the said wheels.

As shown in Fig. 4, the support or holder is 70 adapted to be applied to telephone or telegraph poles. When the support is used for this purpose, the wheels A and B are constructed of glass or some other good non-conducting material, and are mounted upon the 75 pole in a manner similar to the mounting of the support when used on a fence-post.

The operation of my improved support and holder is as follows: On drawing the wire through between the pulley A and the eccentric wheel B in the direction indicated by the arrows the eccentric B rises, in consequence of its axis being to one side of its center, and the pulley-wheel A turns and allows the wire to have a free play over the same. When a 85 desired amount of the wire has been drawn through the wheels in stretching the same, and it is desired to secure it and prevent it from slipping back, the eccentric B engages the wire, and its notches or serrations *b* clamp it 90 against the wheel A, and the greater the back strain upon the said wire the more firmly will it be secured. This support is especially useful in running wires for any purpose up and down inclines or steep hills. The wire is 95 stretched, and when stretched it is clamped between the two wheels and held, and the drawing and consequent securing of the said wire will continue until it is stretched to the desired degree of tension. This support and 100

holder is also adapted to be used with any style of wire, whether plain, barbed, or insulated, acting upon all with equal efficiency as a support, and reliable as a means for securing 5 the same.

It is obvious that slight changes in the construction of the parts could be made and substituted for those shown and described without in the least departing from the nature and 10 principle of my invention.

Having thus described my invention, what I claim as new, and desire to secure by Letters Patent, is—

1. In a wire support and holder, the combination of a pulley-wheel, an eccentric wheel 15 engaging the groove of said pulley-wheel, and a staple for securing the two wheels in the manner substantially as described.

2. As an article of manufacture, the combined wire support and holder comprising the 20 pulley-wheel A, eccentric wheel B, having notches b, extending partially around its periphery and engaging the groove a of the wheel A, and the staple C, one prong, c, thereof passing through the center of the wheel A 25 and acting as its axis, and the other prong, c', passing through the wheel B at one side of its center, substantially as described.

In testimony whereof I affix my signature in presence of two witnesses.

CHARLES WILLISIE.
